(57) CLAIM

I claim the ornamental design for a golf club head, as shown and described.

DESCRIPTION

FIG. 1 is a perspective view of the golf club head embodying the ornamental design of my invention;

FIG. 2 is a view of the bottom of the golf club head of FIG. 1;

FIG. 3 is a view of the rear of the golf club head of FIG. 1; FIG. 4 is a view of the front of the golf club head of FIG. 1;

FIG. 5 is a view of the heel side of the golf club head of FIG. 1; and,

FIG. 6 is a view of the toe side of the golf club head of FIG. 1.

The broken line showings of FIGS. 1-6 are for illustrative purposes only and form no part of the claimed design.
